(57) **CLAIM**

The ornamental design for a multi-accessory mount as shown and described.

DESCRIPTION

FIG. 1 is a left view of a multi-accessory mount according to the disclosure;

FIG. 2 is a right view thereof;

FIG. 3 is a front view thereof;

FIG. 4 is a rear view thereof;

FIG. 5 is a top view thereof;

FIG. 6 is a bottom view thereof;

FIG. 7 is a front perspective view thereof; and,

FIG. 8 is a rear perspective view thereof.

The evenly spaced dashed lines and the unshaded areas adjacent to them depict portions of the multi-accessory mount that form no part of the claimed design.

1 Claim, 6 Drawing Sheets
